UNITED STATES PATENT OFFICE.

WILLIAM J. LAUSTERER, OF JAMESTOWN, NEW YORK, ASSIGNOR, BY MESNE ASSIGNMENTS, TO AUTOMATIC REGISTERING MACHINE CORPORATION, A CORPORATION OF NEW YORK.

LOCKING MECHANISM FOR VOTING-MACHINES.

1,189,838.

Specification of Letters Patent.

Patented July 4, 1916.

Application filed October 14, 1913. Serial No. 795,055.

To all whom it may concern:

Be it known that I, WILLIAM J. LAUSTERER, a citizen of the United States, residing at Jamestown, in the county of Chautauqua 5 and State of New York, have invented certain new and useful Improvements in Locking Mechanism for Voting-Machines, of which the following is a specification.

The object of this invention is to provide 10 a locking device for controlling the operation of the voting machine, that will permit the unlocking of the voting machine for operation and the subsequent locking of the machine against operation and will then prevent any further unlocking of the machine 15 for voting operation until the machine is opened and the lock is especially set therefore. This and other objects of the invention will be fully illustrated in the drawings described in the specification and pointed out 20 in the claims at the end thereof.

In the accompanying drawings, Figure 1 is an elevation of the side of the machine. Fig. 2 is a vertical section on the line 2^x—2^x 25 of Fig. 1. Figs. 3, 4 and 5 are detailed elevations of the locking devices in different positions.

In the accompanying drawings, like reference numerals indicate like parts.

30 In the drawings, reference numeral 1 indicates the casing of a voting machine in which casing is mounted the inspector's knob 2 having a link 3 attached thereto, which link controls the operation of the curtain lever in the manner described in Patent No. 995,424, Gillespie, issued June 13, 1911, 35 see Fig. 54 of said patent.

Pivottally mounted on the side of the casing is a bell crank 4, the lower end of which 40 is adapted to swing in from the inspector's knob and permit the lifting thereof. The upper end of the bell crank is connected to a link 6 which link at its upper end is connected to the stud 7, mounted on the bolt 8 45 of the lock 9. This lock is controlled by the key 10 in the ordinary manner for the purpose of throwing the bolt 8 to lock or release the voting machine.

The stud 7 has a square shank 11 as is 50 shown in Figs. 3, 4 and 5. The lock is especially fitted with a dog 12 and a trigger 13, both of which are mounted on the lock. The dog 12 has an offset portion 14 with which the lower end of the trigger 13 is

adapted to engage. When the dog 12 is 55 moved back to the position shown in Fig. 3, the trigger can be moved back to the position shown in Fig. 3. While in this position, the bolt 8 can be moved up. The shank 11 bearing against the cam portion 15 on the 60 trigger 13 will cause the trigger to move to the right at the top and to the left and up at the bottom. The movement of the trigger to the left and up at the bottom will cause the lower end of the trigger to bear 65 against the offset portion 14 and move the dog 12 back at the top. This backward movement of the dog 12 precedes the upward movement of the bolt 8 with its shank 11 so that the bolt can move to the position 70 shown in Fig. 4. When the bolt is moved down again by the turning of the key, the trigger 13 will remain idly in the position shown in Figs. 4 and 5 but the dog 12 will move to the position shown in Fig. 5, being 75 moved forward by the spring 16. While the dog is in this position, the inspector's knob cannot be raised. As long as the dog remains in this position, voting on the machine cannot be resumed. Access, however, 80 may be gained by the custodian to the inside of the machine and such officer can set the parts again in the position shown in Fig. 3 after which the cycle of operations can be 85 repeated.

I claim:

1. In a machine having an inclosing casing, the combination of means for holding an internal mechanism against actuation and means operated from outside of said casing 90 for locking said holding means in operative position, said locking means being releasable only from the inside of said casing.

2. In a machine, releasable means for holding an internal mechanism against operation, means for locking said holding means against releasing movement, means for operating said locking means from outside of the machine, and latching means actuated by movement of said locking means 100 to hold said locking means in operative position, said latching means being releasable only from the inside of the machine.

3. In a lock the combination of a bolt, a stud thereon, a latch mounted to swing on one side of said stud and a trigger mounted to swing on the other side, a lug on said latch engaged by said trigger to hold the 105

latch out of engaging position, said trigger being engaged by said stud on the forward movement of the bolt to swing the trigger out of engagement with said latch, said latch 5 being adapted to swing into engagement with the stud on the forward movement of the bolt and hold the bolt against a second movement.

4. In a lock the combination of a bolt, a 10 stud thereon, a latch mounted to swing on one side of said stud and a trigger mounted to swing on the other side, a lug on said latch engaged by said trigger to hold the latch out of engaging position, said trigger 15 being engaged by said stud on the forward movement of the bolt to swing the trigger out of engagement with said latch, said latch being adapted to swing into engagement with the stud on the forward movement of the bolt and hold the bolt against a second movement, a spring pressing said latch forward against the stud.

5. In a lock the combination of a bolt, a 20 stud thereon, a latch mounted to swing on one side of said stud and a trigger mounted to swing on the other side, a lug on said latch engaged by said trigger to hold the

latch out of engaging position, said trigger being engaged by said stud on the forward movement of the bolt to swing the trigger 30 out of engagement with said latch, said latch being adapted to swing into engagement with the stud on the forward movement of the bolt and hold the bolt against a second movement, a spring pressing said latch forward against the stud, said latch being first moved back by the movement of the trigger to release the latch.

6. In a machine having an inclosing casing, the combination with a member for releasing mechanism within said casing, of locking means for holding said member against releasing movement, a latch engaging said locking means to hold it against operation, a trigger to hold said latch out of 45 engaging position, said trigger being operated by the bolt to release the said latch on movement of the locking means.

In testimony whereof I affix my signature in presence of two witnesses.

WILLIAM J. LAUSTERER.
